DESIGN FOR A BUMPER OR SIMILAR ARTICLE

Herbert S. Jandus and Bladen M. Short,
Detroit, Mich.

Application September 4, 1934, Serial No. 53,198

Term of patent 7 years

To all whom it may concern:

Be it known that we, Herbert S. Jandus and Bladen M. Short, citizens of the United States and both residing in the city of Detroit, in the county of Wayne and State of Michigan, have invented a new, original, and ornamental Design for a Bumper or Similar Article, of which the following is the specification, reference being had to the accompanying drawing, forming a part thereof.

On the drawing:

Figure 1 is a plan view of a bumper showing our new design;

Figure 2 is an enlarged sectional view taken on the line II-II of Figure 1, showing the arrangement of the bars of the bumper;

Figure 3 is a front view of the bumper; and Figure 4 is a perspective view of the bumper. We claim:

The ornamental design for a bumper or similar article, as shown.
